UNITED STATES PATENT OFFICE.

WILLIAM L. WARNER, OF CHICAGO, ILLINOIS.

HEATER.

SPECIFICATION forming part of Letters Patent No. 709,947, dated September 30, 1902.

Application filed September 26, 1901. Serial No. 76,606. (No model.)

To all whom it may concern:

Be it known that I, WILLIAM L. WARNER, a citizen of the United States, residing at Chicago, in the county of Cook and State of Illinois, have invented certain new and useful Improvements in Heaters, of which the following is a specification, reference being had to the accompanying drawings, forming a part thereof.

10 The purpose of this invention is to provide improved construction of a hot-air furnace in which the heat is derived from the flame of a burner.

The specific purposes are, first, to utilize 15 more fully than has heretofore been done the heat of the gaseous products of combustion, causing them to pass into the chimney at the lowest temperature consistent with proper draft; second, to make it possible to direct 20 the hot-air currents readily to any register or room and to furnish heat for any one or more separate registers or apartments without heating or producing heat enough to supply any additional registers or apartments 25 which it may not be desirable to heat—that is, to operate the furnace to any extent necessary to heat any limited proportion of the total space for which the furnace is calculated and direct the heat products to that 30 limited proportion only, so that the furnace shall operate as economically for heating a portion as for heating the whole of the house in which it is located.

The invention consists in the features of 35 construction which are set out in claims.

In the drawings, Figure 1 is a side elevation of the furnace having my invention, the wall being broken away at the side in view to show the interior construction. Fig. 2 is 40 a section at the line 2 2 of Fig. 1. Fig. 3 is a section at the line 3 3 on Fig. 2.

A is a chamber, within which are located air-circulation ducts B B B of any desired number, according to the number of registers 45 or apartments to be heated by means of the heater which comprises said chamber A. The ducts B comprise each a plurality of horizontal or approximately horizontal pipe-sections b b, &c., connected by return bends 50 successively in continuous course, the uppermost of the said horizontal sections leading out through the wall of the chamber and con-

stituting the cold-air inlet, while from the lowest of said pipe-sections b the outlet-pipe b' leads upward and emerges from the heater 55 at the upper part and constitutes the hot-air-conducting pipe to the register or apartment to be supplied with heat thereby. Underneath the lowest section b of each of the ducts b b, &c., there is a row of gas-jets CCC, &c. 60 Preferably these jets issue from gas-pipes c c, two of which extend parallel with each other under and parallel with the air-pipes b, which they serve, the terminals from which the jets are emitted being arranged in pairs, one issuing 65 from each of the two parallel gas-pipes in direction inclined toward each other and toward the middle of the air-pipe b to be heated, so that the jets tend to impinge upon each other undersaid air-pipe. The bottom of the 70 heated chamber is formed with slots a a extending longitudinally under each of the air-pipes b, and has flanges a' a' extending up at the margin of said slots, the gas-pipes c c for each air-pipe being located in the slot between and preferably close to the flange, as 75 shown in Fig. 2. There is thus provided ingress for air to support combustion directly under each of the pipes and between the gas-pipes c c, so that when the jets are burning the 80 air necessarily is drawn between them at the plane at which they tend to impinge upon each other, thus producing thorough combustion, while at the same time the gas products of combustion rising from the jets and directed 85 by the flanges a' a' are projected upward against the air-pipe b, so that they are diverted in both directions around said pipe. Preferably, but not necessarily, the chamber 90 has vertical longitudinal partitions A' A' extending part of the height of the chamber between the several air-ducts B B B, forming thus a subchamber for each of said ducts. In order to more perfectly insure the enveloping of the successive pipe-sections b in the 95 gaseous products of combustion as they rise, I prefer to give said pipe-sections a staggered arrangement, setting them alternately nearer the opposite walls of the subchamber in which they stand, so that while one pipe is 100 very near the one wall and remote from the other the second is more remote from the one wall and nearer the second. The rising current of combustion, dividing as it strikes

the lowest section of pipe *b*, will pass by it in larger proportion at the side where the large aperture is found; but a portion will also pass up between the narrower space at the other side. The larger portion, which passes through the larger space, not finding free path at the same side past the next pipe, will be diverted under the next pipe to reach the wider opening at the opposite side, a portion only passing up through the narrower space. Thus the total result will be that a limited current, corresponding to the narrower space, will pass up at each side along the walls of the subchamber and close to the pipes which are near the wall, and the remaining portion will zigzag back and forth between and around the pipes, thus reaching all portions of the surface with about equal effect. It may be understood that if the space were equal on the two sides the current would divide into two direct upward currents along the sides and would not strike under nor circle about any of the pipes except the lowest.

The chamber *A* has three walls, with two interspaces. The outer wall *A*² is perforated at the upper part on all sides, the partitions *A'* terminating at about the level of the uppermost horizontal pipe-section *b* and all the subchambers being merged above the point opposite the perforated part of the wall *A*². The intermediate wall *A*³ is similarly perforated at the lower part. The outermost wall has, preferably at the top, but in any event at the upper part, a single aperture *A*⁴ for the pipe *a*⁴, leading to the chimney, termed the "smoke-pipe," by which the products of combustion have final discharge and are conducted. This arrangement compels the products of combustion, after circulating around the air-pipes in all the subchambers, to pass down between the inner and intermediate walls *A*² and *A*³ and thence up between the intermediate and outer walls before escaping to the chimney. Any portion of heat remaining in the gases after they have circulated around the air-pipes more than is necessary for draft may be parted with as the gases pass back and forth between the several walls, the outer wall being thus considerably heated even after the air-pipes, with the air circulating around them, have extracted all the heat they can from the gases. The heat thus radiated from the outer wall is made available by inclosing the entire chamber *A* in a jacket *E*, from which one or more hot-air pipes *F'* *F*' may lead to registers not too remote, preferably on the same floor or next floor above that on which the heater is located. A suitable air-inlet may be provided for the air-chamber, formed between the furnace-chamber *A* and the jacket *F*. The air in this chamber will not be so hot as that which passes through the pipes if the circulation is properly regulated in the latter; but it will be sufficient to serve nearby apartments. Each of the pipe systems *B* having its own cold-air inlet and being provided with

its own controlling valve or damper *M* and heated by an independent system of gas-jets controlled by a separate valve *N* *N*, it will be seen that only so many rows of jets may be lighted as there are independent apartments to be heated and registers to be served and that each row of gas-jets may be regulated so as to heat its own air-pipe to such degree only as necessary, so that different apartments for which different temperature is desired may be served each according to requirement, the consumption of fuel being according to the demand for heat at each apartment, so that as wide range of temperature may be maintained in a house served by the same heater as if each apartment had a separate furnace.

It will be obvious that other fluid than gas may be used, provided it is adapted to produce flame which can be controlled under the air-ducts, and this involves practically that it shall be fluid fuel, which is conducted to suitable burners, located as indicated.

I claim—

1. A heater comprising a chamber; approximately horizontal pipes in the chamber one above another connected consecutively in continuous course, the uppermost pipe being extended out through the wall of the chamber and serving as the cold-air inlet; and a pipe leading from the lowest of said pipes upward and out of the chamber; burners having their flames directed against the lowest pipe, the chamber having ingress for air to support combustion below the lowest pipe, and having egress for the products of combustion after passing to the upper part.

2. A heater comprising a chamber and plurality of air-ducts therein, each consisting of a plurality of approximately horizontal sections of pipe connected consecutively in continuous course, one above the other, the upper section of each duct leading out through the wall of the chamber, and serving as a cold-air inlet for the air-duct to which it pertains, the lowest section having connection leading upward and out of the chamber; independently-controlled burners under the lowest section of each of the ducts and means for causing the flame from such burner to circulate about the several sections of the ducts, respectively, under which they are located, to heat said ducts each independently of the remainder.

3. A gas-heater comprising a chamber and a plurality of air-ducts therein, each duct being arranged in successive pipe-sections one above another connected in continuous course emerging from the chamber at the upper end of the course, and having connection from the lowest section leading upward and also emerging from the chamber; burners located under said ducts respectively, and means for independently controlling said burners, the chamber having vertical partitions between said several air-ducts, whereby the flame and the current of products of combustion from

each burner is confined about the pipe-section of the duct under which the burner is located, the chamber having escape for the products of combustion at the upper part 5 and ingress for air at the lower part.

4. A gas-heater comprising a chamber and air-ducts therein, consisting of successively-connected pipe-sections one above another, forming a continuous course, said course of 10 pipe leading out of the chamber at the upper part, and having connection from the lower end leading upward and out of the chamber: burners having their flame directed against the lowest section of said course and means 15 for controlling such burners; the chamber having escape for the products of combustion at the upper part, and ingress for air to support combustion at the lower part.

5. A gas-heater comprising a chamber and 20 an air-pipe consisting of zigzag courses one above another continuously connected, the upper course leading out of the chamber, and the lowest course leading upward and out of the chamber; burners underneath the lowest 25 course, with means for controlling the same, the chamber having an interior false wall, an intermediate and outer wall with two inner spaces, the inner false wall being apertured at the upper part to permit escape for the products of combustion, the intermediate wall being apertured at the lower part to continue such escape, and a final discharge being provided through the outermost wall at the upper part; whereby the gaseous products of 30 combustion are taken from the top of the chamber and forced to circulate downward and upward before final escape.

6. A gas-heater comprising a chamber and air-duct in the chamber, consisting of a series of approximately horizontal sections 40 one above another connected in continuous course, such ducts leading out of the chamber at the upper end, and having from its lower end connection leading upward and out of the 45 chamber; burners under the lowest pipe-section; the chamber having ingress for air to support combustion, and egress for the product of combustion above the duct, said sections of the air-duct being placed with a nar-

row space at one side and a wider space at 50 the opposite side for the passage of the gases of combustion, alternate sections having the spaces of corresponding width on opposite sides; whereby the current of gases of combustion is forced to circulate back and forth 55 between the pipe-sections as it rises to escape from the chamber.

7. A gas-heater comprising a chamber and air-pipe duct in the chamber, consisting of successive sections one above another connected in continuous course, the uppermost section leading out of the chamber at the upper end, and the duct having connection from the lower end leading upward and out of the chamber: burners having their flame directed 60 against the lowest section of the duct with means for controlling the same; the chamber having a false inner wall apertured at the upper part for the escape of gases and having a second wall outside such false wall apertured 65 at the bottom for such escape.

8. A gas-heater comprising a chamber and plurality of air-ducts therein each consisting of successively-connected pipe-sections, and elbows forming a continuous course leading 75 out of the chamber at the upper part and having connection from the lower end leading upward out of the chamber; burners under the lower section of each such course means for controlling such burners; the wall of the 80 chamber having an interspace and having apertures at the lower part leading into such interspace and apertures for the escape for the products of combustion leading from said interspace at the upper part of the chamber and 85 jacket inclosing the chamber with an intervening air-space; accesses for air at the lower part of said air-space and a heating-pipe leading from the air-space at the upper part. 90

In testimony whereof I have hereunto set my hand, in the presence of two witnesses, at Chicago, Illinois, this 16th day of September, A. D. 1901.
